DISTRIBUTION TRANSFORMER

Alphonse J. Marchand, Schenectady, N.Y., assignor to
General Electric Company, a corporation of New York

Filed Sept. 23, 1969, Ser. No. 19,263

Term of patent 14 years

Int. Cl. D13—02

U.S. Cl. D26—15

Fig. 1.

Fig. 2.

Fig. 3.

Fig. 4.

FIG. 1 is a top plan view of a distribution transformer showing my new design;

FIG. 2 is a side view of the transformer design, the other side being a mirror image;

FIG. 3 is a rear elevation view on a reduced scale of the transformer design; and

FIG. 4 is a perspective view thereof.

I claim:

The ornamental design for a distribution transformer, as shown and described.
